DESIGN FOR A PLANTER LAMP

Robert E. Gifford, Farnsworth, Ill.

Application June 20, 1947, Serial No. 139,837

Term of patent 3½ years

(Cl. D48—20)

To all whom it may concern:

Be it known that I, Robert E. Gifford, a citizen of the United States of America, residing at Farnsworth, Great Lakes Naval Reservation, in the county of Lake and State of Illinois, have invented a new, original, and ornamental Design for Planter Lamp, of which the following is a specification, reference being had to the accompanying drawing, forming a part thereof.

Referring to the drawing;

Figure 1 is a three-quarter front view in perspective, showing my new design; and

Figure 2 is a similar rear view in perspective.

I claim:

The ornamental design for a planter lamp, as shown.

ROBERT E. GIFFORD.
